**R. BURNS & C. K. PICKLES.
PNEUMATIC HAMMER.**

(No Model.)

Inventors,
Robert Burns and
Charles K. Pickles,

by Robert Burns Atty.

UNITED STATES PATENT OFFICE.

ROBERT BURNS, OF CHICAGO, ILLINOIS, AND CHARLES K. PICKLES, OF ST. LOUIS, MISSOURI; SAID PICKLES ASSIGNOR TO BURT E. TILDEN, OF CHICAGO, ILLINOIS.

PNEUMATIC HAMMER.

SPECIFICATION forming part of Letters Patent No. 635,422, dated October 24, 1899.

Application filed July 15, 1899. Serial No. 723,999. (No model.)

To all whom it may concern:

Be it known that we, ROBERT BURNS, of Chicago, in the county of Cook and State of Illinois, and CHARLES K. PICKLES, of St. Louis, in the State of Missouri, citizens of the United States, have invented certain new and useful Improvements in Pneumatic Hammers; and we do hereby declare the following to be a full, clear, and exact description of the same, reference being had to the accompanying drawings, forming a part of this specification.

The present invention relates to that type of pneumatic engines in which the reciprocating piston constitutes a hammer adapted to deliver a series of rapidly-recurring blows to a chipping or other tool, the shank of which is located in the path of such impact-piston and constitutes an end closure for the lower piston-chamber.

The objects of the present improvement are, first, to provide a simple and efficient sectional formation and arrangement of the main cylinder for the impact-piston and the valve-block and housing for the reversing-valve, which permits of a ready and convenient detachment of the parts for cleaning, repair, and replacement of worn parts; second, to provide means for connecting the handle, main cylinder, and valve-block and housing together in a rigid and substantial manner; third, to provide means self-contained within the hammer for the automatic lubrication of the hammer parts while in operation. We attain such objects by the construction and arrangement of parts illustrated in the accompanying drawings, in which—

Figure 1 is a longitudinal sectional elevation at line x x , Fig. 3, illustrating the position of the parts at the commencement of the forward stroke of the impact-piston of the present pneumatic hammer; Fig. 2, a fragmentary longitudinal section at line x' x' , Fig. 3, illustrating the position of the parts at the ending of such forward stroke of the impact-piston and with the valve reversed to effect a backward or return movement of such piston; Fig. 3, a horizontal section at line x^2 x^2 , Figs. 1 and 2; Fig. 4, a side elevation of the

valve-block in a detached condition; Fig. 5, 50 a side elevation of the reversing-valve in a detached condition.

Similar numerals of reference indicate like parts in the several views.

Referring to the drawings, 1 represents the main cylinder or casing, the lower end of which is provided with a guide-bushing 2, that receives the shank portion of the chipping or other tool, as usual in the present type of hammers.

3 is the cylindrical impact-piston, adapted to have reciprocating movement in the bore of the main cylinder 1 and formed with an annular recess or chamber 4 near its upper end. Such piston is also provided with reduced axially-arranged end extensions 5 and 6, the lower extension 5 constituting the impact portion of the piston to impact upon the shank of the chipping or other tool employed, while the upper extension 6 is adapted to enter a central chamber in the valve-block of the hammer to effect a cushioning action upon the piston as it nears the end of its upward or return stroke. Such piston is also formed with a port or passage 7, connecting the annular passage or chamber 4 of the piston with the lower piston-chamber, as illustrated in Fig. 2.

8 is the circularly-enlarged base of the valve-block of the present invention, which constitutes a head for closing the upper end of the main cylinder 1, and offset to fit the same, as illustrated in Figs. 1 and 2.

9 is an axially-arranged hollow cylindrical portion of the valve-block, closed at its upper end and open at its lower end to form an axially-arranged chamber adapted to receive the upper cylindrical extension 6 of the impact-piston, as heretofore described.

10 is the cylindrical valve-housing, arranged concentrically to the cylindrical portion 9 of the valve-block and offset or counterbored to form, in connection with such valve-block, upper and lower valve-chambers 11 and 12 of differential areas, the upper one 95 of said chambers having an area smaller than the lower one, as shown. Said valve-housing 10 is preferably of an external diameter

equal to that of the main cylinder 1 and fits against the offset upper end of the enlarged base 8 of the valve-block, as shown.

13 is the reversing-valve of an annular form, 5 with an internal diameter equal to the external diameter of the cylindrical portion 9 of the valve-block and adapted to have its seat thereon.

The lower portion of the valve 13 is formed 10 by an enlarged head 14, that has movement in the lower enlarged valve-chamber 12, while the upper and main portion of the valve is of a lesser diameter and is adapted to have movement in the correspondingly-reduced up- 15 per valve-chamber 11. As so constructed the reversing-valve is of a differential nature, having differential pressure areas on its opposite faces and adapted to operate under differential effects of fluid-pressure, as usual 20 in the present type of reversing-valve, and the arrangement is such that the motive fluid will exert constant pressure upon the upper and smaller area of the valve.

15 is an annular internal exhaust-chamber 25 in the main portion of the reversing-valve 13, and 16 are openings through the wall of such chamber, the chamber and openings being adapted to control communication between the upper and lower piston-chambers of the 30 main cylinder and the exhaust-port 17 in the valve-housing 10, that opens to the atmosphere, as shown in Figs. 1, 2, and 3.

18 is a longitudinal port or passage formed 35 in the main cylinder 1, the valve-block head 8, and valve-housing 10, the upper end of which has connection with the lower end of the enlarged lower valve-chamber 12, while its extreme lower end opens into the interior of the main cylinder 1 at a point that will 40 permit of an exhaust of the motive fluid from the lower valve-chamber 12 when the impact-piston 3 is in its upper position, as illustrated in Fig. 1.

20 is a longitudinal port or passage formed 45 like the port or passage 13 in the main cylinder 1, the valve-block head 8, and the valve-housing 10, with its upper end communicating with the pressure-supply chamber at the upper end of the hammer, while its lower end 50 communicates with the interior of the main cylinder 1 at a point opposite the small lateral branch 19 of the longitudinal passage 18, heretofore described, the arrangement being such that as the annular peripheral chamber 55 4 of the impact-piston uncovers said passages to put the same into communication the fluid-pressure will be introduced into the lower valve-chamber 12 to force the reversing-valve 13 into its upper position, as indicated in Fig. 60 2. At the same time a restricted supply of motive fluid is admitted into the lower piston-chamber through the port or passage 7 to effect an upward or return movement of the impact-piston 3.

65 21 are one or more ports or passages through the upper end of the cylindrical portion 9 of the valve-block and in the path of the upper

end of the reversing-valve 13 and through which motive fluid is admitted to the upper piston-chamber in a controllable manner. 70

22 is a relief or exhaust port or passage formed in the main cylinder 1, the valve-block base 8, and valve-housing 10 and connecting the lower piston-chamber with the atmosphere in a controllable manner, its lower end 75 communicating with the lower end of the lower piston-chamber, while its upper end opens into the reversing-valve chamber at a point adjacent to the exhaust-chamber 15 of the main reversing-valve, so that with the 80 parts in the position illustrated in Fig. 1 the port or passage 22 will be in communication with the atmosphere through the exhaust-chamber 15 and openings 16 of the reversing-valve, and with the parts in the position illustrated in Fig. 2 the exhaust nature of the 85 passage 22 will be rendered inactive by the lower enlarged head 14 of the reversing-valve closing communication between said passage and the exhaust-chamber of the valve. 90

23 is the attaching sleeve or hub of the hammer-handle, fitting over the valve-housing 10, the valve-block base 8, and the circular flange 24 on the upper end of the main cylinder 1, the bore of such hub or sleeve being formed with annular offsets to engage the upper marginal edges of the valve-housing 10 and the valve-block base 8 and hold the same in proper relative position. 95

The extreme lower end of the sleeve or hub 100 23 is internally screw-threaded to receive the annular nut 25, that has engagement against the under side of the flange 24 of the main cylinder, as shown in Figs. 1 and 2, the construction being such that said nut is adapted 105 to forcibly clamp and hold the main cylinder, valve-block, and valve-housing in proper relative position.

26 is a transverse locking-bolt passing 110 through ears 27, that are located on either side of a vertical slit 28 in the lower end of the sleeve or hub 22 of the hammer-handle, the construction being such as to afford a substantial means for contracting the lower end of said sleeve upon the annular nut 25 after 115 an adjustment has been attained and prevent a jarring loose of the parts in use.

29 is the supply-passage for the motive fluid, formed in one of the branches 30 of the hammer-handle and communicating at its 120 lower end with the main supply-chamber 31 at the upper end of the hammer, while its upper end is intersected by the casing 32 of the manually-actuated controlling-valve 33.

In the construction illustrated in Fig. 1 the 125 valve 33 is of the reciprocating-piston type, formed with an annular peripheral passage or chamber 34, adapted to register with oppositely-arranged orifices 35 in the stationary valve-casing 32 and by its movement to control the supply of motive fluid to the hammer mechanism.

36 is a spring tending to hold the valve 33 in its closed condition.

37 is a pivoted trigger or thumb-lever having engagement with one end of the valve and adapted to impart an opening movement to the same.

5 In the present invention the shank portion of the valve 33 is of an enlarged formation that is chambered out to constitute an oil chamber or reservoir 38, the filling-opening of which extends out through the forward end 10 of the valve and is closed by a screw-threaded bolt or stopper 39, as shown in Fig. 1, so as to afford a convenient means for filling the oil-reservoir.

40 is the oil-feeding orifice from the reservoir, located in the sunken wall of the annular passage 34 of the valve, which orifice is controlled by a needle-valve 41, also arranged in such cavity or passage 34. With the described construction the oil will feed from the orifice 40 into the annular passage 34, directly in the path of the incoming motive fluid, so as to be carried by the same directly to the various moving parts of the hammer to effect a very perfect and efficient lubrication of the same.

The operation of the present hammer mechanism is as follows: Starting with the parts in the position illustrated in Fig. 1, the motive fluid from the main supply-chamber 31 passes through the ports 21 into the valve-block chamber to press upon the upper end extension 6 of the impact-piston 3 and acting against the decreased area thereof imparts a light initial movement to the piston, which from practical experience is found to be very efficient in reducing the amount of jar or vibration that is usual in the present type of hammers. With the end extension 6 of the impact-piston forced out of the chamber of the valve-block the full area of the piston is exposed to the motive fluid and an active and forcible downward movement of the piston takes place. In such downward movement of the piston the pressure of the motive fluid continues until the annular chamber 4 of the piston registers the port or passage 20 with the opening 19 of the port or passage 18, after which the remainder of the active stroke of the piston is dependent upon its momentum. With the port or passage 20 and opening 19 in communication by means of the annular passage 4 of the piston the motive-fluid pressure is admitted to the lower enlarged valve-chamber 12, against the enlarged head 14 of the reversing-valve, to force said valve into its upper position, as indicated in Fig. 2, to cut off the supply of motive fluid to the upper piston-chamber through ports 21 and by means of its exhaust-chamber 15 and openings 16 establish communication between the upper piston-chamber and the exhaust-port 17 to the atmosphere. At the same time motive fluid passes down through the restricted port or passage 7 in the piston 65 into the lower piston-chamber to cause a comparatively slow return or upward movement of the piston. With the return of the piston

to its upper position the lower end of the port or passage 18 is uncovered and communication between the same and the lower piston-chamber is established, as illustrated in Fig. 1, which allows the pressure in the lower valve-chamber 12 to exhaust therefrom and permit the constant fluid-pressure upon the upper and reduced end of the valve to again 75 force the same into its lower position to commence a fresh cycle of the operations just described.

Having thus fully described our said invention, what we claim as new, and desire to secure by Letters Patent, is—

1. In a pneumatic hammer, the combination of a piston, a piston-cylinder, a valve-block closing the end of such cylinder and provided with a hollow cylindrical extension forming 85 a valve-seat, a valve-housing, and a fluid-actuated valve surrounding said valve-seat and having differential pressure areas, the reduced pressure area of the valve being under constant motive-fluid pressure, and the larger 90 pressure area of the valve under an intermittent motive-fluid pressure, substantially as set forth.

2. In a pneumatic hammer, the combination of a piston, a piston-cylinder, a valve-block 95 closing the end of such cylinder and provided with a hollow cylindrical extension forming a valve-seat, a valve-housing, a fluid-actuated valve surrounding said valve-seat and having differential pressure areas, the reduced pressure area of the valve being under constant 100 motive-fluid pressure, and a passage controlled by the piston for intermittently admitting the motive fluid to the larger pressure area of the valve, substantially as set forth. 105

3. In a pneumatic hammer, the combination of a piston, a piston-cylinder, a valve-block closing the end of such cylinder and provided with a hollow cylindrical extension forming 110 a valve-seat, a valve-housing, a fluid-actuated valve surrounding said valve-seat, and having differential pressure areas, the reduced pressure area of the valve being under constant motive-fluid pressure, a passage controlled by the piston and opened by the latter on its 115 downstroke to admit motive fluid to the larger area of the valve, and an exhaust-passage leading from said larger area of the valve and opened by the piston in its upward stroke, substantially as set forth. 120

4. In a pneumatic hammer, the combination of a piston, a piston-cylinder, a valve-block closing the end of such cylinder and provided with a hollow cylindrical extension forming 125 a valve-seat, a valve-housing, a fluid-actuated valve surrounding said valve-seat, and having differential pressure areas, the reduced pressure area of the valve being under constant motive-fluid pressure, and the larger pressure area of the valve under an intermittent motive-fluid pressure, and a longitudinal passage connecting the lower piston-chamber with the exhaust-chamber of the valve, substantially as set forth. 130

5. In a pneumatic hammer, the combination of a piston, a piston-cylinder, a valve-block closing the end of such cylinder and provided with a hollow cylindrical extension forming a valve-seat, a valve-housing, a fluid-actuated valve surrounding said valve-seat and having differential pressure areas, the reduced pressure area of the valve being under constant motive-fluid pressure, and the lower pressure area of the valve under an intermittent motive-fluid pressure, a longitudinal passage in the cylinder and a passage through the piston, and an annular peripheral chamber in the piston adapted to admit motive-fluid pressure 10 to the lower piston-chamber, substantially as set forth.
6. In a pneumatic hammer, the combination of a piston, a piston-cylinder, a valve-block closing the end of such cylinder and provided with a hollow cylindrical extension forming a valve-seat, a valve-housing, a fluid-actuated valve surrounding said valve-seat, and having differential pressure areas, the reduced pressure area of the valve being under constant motive-fluid pressure, and passages controlled by the piston, and adapted to introduce motive-fluid pressure into the enlarged valve-chamber to hold the valve in its upper position, substantially as set forth.
7. In a pneumatic hammer, the combination of a piston formed with a reduced cylindrical extension on its upper end, a piston-cylinder, a valve-block closing the upper end of the cylinder and provided with a hollow cylindrical extension forming a valve-seat, and a chamber to receive the extension on the upper end of the piston, ports connecting the upper end of such chamber with the motive-fluid-supply chamber, and a valve controlling said ports, substantially as set forth.
8. In a pneumatic hammer, the combination of a piston, a piston-cylinder provided with a flanged upper end, a valve-block closing the end of such cylinder, a valve-housing fitting the valve-block, a handle-attaching sleeve or hub fitting over the respective parts and formed with offsets to engage the valve-housing and valve-block, the lower end of such hub being internally screw-threaded, and an annular nut screwing into such lower end of the hub and abutting against the flange of the main cylinder to clamp the various parts together, substantially as set forth.
9. In a pneumatic hammer, the combination of a piston, a piston-cylinder provided with a flanged upper end, a valve-block closing the end of such cylinder, a valve-housing fitting the valve-block, a handle-attaching sleeve or hub fitting over the respective parts and formed with offsets to engage the valve-housing and valve-block, the lower end of such hub being internally screw-threaded and formed with a vertical slit, lugs at the adjacent side of said slit, a clamping-bolt passing through said lugs, and an annular nut screwing into the lower end of the hub and abutting against the flange of the main cylinder, substantially as set forth.
10. The combination in a pneumatic hammer of a reciprocating controlling-valve for the motive fluid, the shank of which is formed with an oil chamber or reservoir and an outlet therefrom, a needle-valve controlling said outlet and located in the annular peripheral motive-fluid passage of the valve, substantially as set forth.
11. The combination in a pneumatic hammer of a reciprocating controlling-valve for the motive fluid, the shank of which is formed with an oil chamber or reservoir, the filling-neck of which extends through one end of the valve, and a stopper closing said filling-neck, the said reservoir having an outlet adapted to deliver the oil in the path of the motive fluid, substantially as set forth.

In testimony whereof witness our hands this 3d day of July, 1899.
